UNITED STATES PATENT OFFICE.

CLYDE J. COLEMAN, OF NEW YORK, N. Y., ASSIGNOR TO THE HALL SIGNAL COMPANY,
A CORPORATION OF MAINE.

RAILWAY SIGNALING SYSTEM AND APPARATUS.

1,160,993.

Specification of Letters Patent. Patented Nov. 16, 1915.

Application filed September 22, 1908, Serial No. 451,215. Renewed October 27, 1910. Serial No. 589,422.

To all whom it may concern:

Be it known that I, CLYDE J. COLEMAN, a citizen of the United States, residing in New York, county and State of New York, have invented certain new and useful Improvements in Railway Signaling Systems and Apparatus, of which the following is a specification.

My invention relates to electric signaling systems for railroads, and is especially adapted for use with railroads employing electric traction.

My invention is further especially adaptable for use in block systems wherein there are abnormally long blocks.

In prior systems many difficulties have been met with in causing the proper operation of the signal when the block is abnormally long. In order to avoid these difficulties I have provided a system in which the signal will operate equally as well in an abnormally long block as in a short block, and yet the system is so arranged that only a minimum signal controlling current in the track is required and the whole system is very economical and effective.

I have shown my invention and have especially designed the same in connection with a system in which movable arms or semaphores are automatically operated to advise the engineer as to the condition of the track in the block or blocks that he is approaching.

In making use of the terms signal and signaling system I do not intend to suggest that my invention is limited to this particular type of system but wish it to be considered that by such terms, which I have for purposes of simplicity used throughout this specification and throughout the claims, I include systems in which the automatic devices may operate alarms or set switches or act upon a train circuit or act upon any other apparatus in such a way as to automatically give warning to an operator or control the operation of the cars.

In carrying out one form of my invention I provide a bond of negligible impedance between the track rails at each end of the blocks and also one near the middle of the blocks. Approximately half way between these bonds I apply to the track rails a source of electromotive force, preferably alternating, and in close proximity to the bonds I place coils in inductive rela-

tion to the track rails. These coils are so connected and arranged that the current therein will operate electromagnetic devices which in turn control the operation of the signal or signals. The coils at each side of a bond that is intermediate the block ends supply current respectively to the two co-operating members of a single relay, so that the relay places the signal to danger if either of said coils is deprived of current by the short-circuiting action of a train.

Further and more specific features and advantages of my invention will more clearly appear from the detailed description given below taken in connection with the accompanying drawing which shows diagrammatically one form of my invention.

In the drawing 1, 1, represent track rails which are continuously electrically conductive throughout the portions of the track shown. These track rails are shown divided into blocks A, B and C, and at the ends of the various blocks the track rails are connected with each other by bonds 2. Intermediate the bonds 2, and generally substantially half way therebetween, I connect the rails, 1, 1 with a similar bond 3.

4 and 5 represent swinging semaphore arms placed at substantially the entrance to the blocks B and C respectively. These arms may be of the ordinary construction of such arms, being arranged to have a gravity danger position, except as controlled by electro-responsive devices acting directly or indirectly upon them. Each of these arms is to stand at the danger position when there is a train on the track in the block beyond the arm, or when there is any other condition that takes away the current from the electro-responsive devices governing the same. The bonds 2 and 3 are of relatively low or negligible impedance so as to afford so small an opposition to current that a signal controlling current supplied to the rails at one side of such a bond will not pass beyond the bond in sufficient quantity to have any material effect upon devices there located. Preferably the bonds are simply straight conducting bars of ample cross-section thoroughly connected with both rails.

Where, as in this case, a signaling system is used employing alternating current, it is important that the bonds between the rails be of low impedance.

6 represents a main source of signal con-

trolling current which in the present instance is shown to be an alternating current dynamo. Referring to the block B the source 6 is connected to primaries 7 and 8 of transformers, the secondaries 9 and 10 of which supply the track rails, substantially half way between the various bonds, with signal controlling currents. Thus the current furnished by each transformer sec-

10 ondary is normally divided into two circuits, one through the rails toward and through the bond 2 and the other through the rails toward and through the bond 3. 11, 12, 13, 14, 15 and 16 are coils placed 15 in inductive relation to the rails so as to have a current produced therein when the signal controlling current is flowing through the rails adjacent to said coils. I prefer to place these coils at points adjacent 20 to the bonds as shown, being just far enough away from said bonds so that the current in the bonds will not have a disturbing inductive effect upon the coils.

The currents from the coils 12 and 15 are 25 supplied to relays 17 and 18 respectively and the currents from coils 13 and 14 are supplied to a relay 19. These relays 17, 18 and 19 control the local signal circuit 20. The relays 17 and 18 are shown as solenoidal 30 coils which act to draw down contact levers 21 and 22 respectively in opposition to springs 23. The relay 19 is shown as a motor arrangement having its field 24 supplied by the coil 13 and its armature 25 supplied by the coil 14. Attached to the armature 25 is a contact lever 26. When the current at the right hand side of the bond 3 is diverted therefrom, as through the axles of a train truck on the track, no current will be 40 produced in the armature 25. When the current at the left hand side of the bond 3 is diverted therefrom no current will be produced in the field 24. If a train is so located that the current is diverted from 45 both coils 13 and 14 simultaneously, both the armature 25 and field 24 will be deenergized. In any of these cases the turning force applied to the armature 25 is taken away and the contact arm 26 will fall to a 50 more nearly vertical position by force of gravity. This action opens the local circuit 20 so that the magnet 27 will become deenergized causing the semaphore arm 4 to move by gravity to the danger position. 55 Similarly when the signal controlling current is diverted from the track rails near either of the bonds 2 and coils 12 or 15, the corresponding solenoid 17 or 18 will become deenergized so that the spring 23 will 60 cause the corresponding contact lever to open the local circuit and set the signal at danger as before. It will therefore be seen that the block B is divided into four parts a, b, c, and d, the dividing points being at 65 the bonds 2, 3, and transformer secondaries

9 and 10. When a train or car enters any one of these four parts of the track the current furnished by the transformer secondary to that part is diverted through the axles of the train or car from the rails adjacent the coil at that part of the track, thus deenergizing said coil in inductive relation with that part of the track. This causes the corresponding relay device to become deenergized so that the local circuit 20 is 70 opened and the semaphore set at danger. The blocks A and C may have a similar or the same arrangement as that shown in block B. Coil 11 is shown located in block A and coil 16 and semaphore 5 and solenoid 80 28 are shown located in block C.

At 29 I have shown in dotted lines the axle and wheels of a truck just leaving the block B. Thus the current in portion d of the track furnished by the transformer 85 secondary 10 is diverted from those portions of the track adjacent the coil 15 and no current is derived from said coil. Consequently the lever arm 22 will assume the position shown in dotted lines, thus opening the circuit 20 and causing the semaphore arm 4 to assume the position shown in dotted lines. The solenoid 27 and circuit 20 receive energy from the source 6 by means of a transformer 33.

The energy for traction purposes may be supplied by a generator 30 herein shown as furnishing a direct current, and one side of the generator is connected to the track rails as at 31, so that they may be used for the return traction current. Since the bonds 2 and 3 have a negligible impedance and resistance the traction current returns equally through both rails and thus does not affect the coils 11, 12, 13, 14, 15 or 16. The traction current may be fed to a third rail or to a trolley as by conductor 32.

It is evident from the above that I have provided a system which is especially adapted for exceptionally long blocks. By providing a bond and various sources intermediate the ends of the block I am enabled to operate the relays with small signal controlling currents and at small voltages.

I have described specific embodiments of my improvements and in some detail, but I desire it to be understood that my invention is broader than such details, and is not limited to any particular embodiment nor to the specific details of construction and arrangement shown and described.

What I claim and desire to secure by Letters Patent, is:

1. In a railway block signaling system bonds at the ends of the block, a bond intermediate the ends of the block, means for supplying current to the rails intermediate the bonds, electro-responsive devices connected and arranged to be actuated in one direction or the other according to 125 130

whether or not the current from the said rails is diverted from the rails between a source and one of said bonds, and signal controlling devices operatively related to 5 said electro-responsive devices and governed thereby.

2. A railway block signaling system having bonds at the ends of the block, a bond intermediate the ends of the block, sources 10 of electromotive force applied to the rails intermediate the bonds, signal controlling devices at points along said track and electro-responsive devices for governing said signal controlling devices.

15 3. A railway block-signaling system having bonds at the ends of the block, a bond intermediate the ends of the block, means for supplying current to the rails, signal controlling devices at points along said 20 track, and electro-responsive devices arranged and connected to govern said signal controlling devices.

4. A railway block signaling system, having bonds at the ends of the block, a bond 25 intermediate the ends of the block, means for supplying signal controlling current to the rails, and electro-responsive devices at points in said block for controlling the operation of the signal.

30 5. A railway block signaling system having bonds at the ends of the block, a bond intermediate the ends of the block, means for supplying signal controlling current to the rails between the intermediate and end bonds, signal controlling means and an 35 electro-responsive device arranged at each bond for governing said signal controlling means.

6. A railway block signaling system having a bond at each end of the block, a bond 40 intermediate the ends of the block, sources of signal controlling current applied to the rails intermediate the bonds, signal controlling means and an electro-responsive device 45 arranged at each bond for governing said signal controlling means.

7. A railway block signaling system having a bond at each end of the block, a bond intermediate the ends of the block, means 50 for supplying a signal controlling current to the rails intermediate the bonds, a coil in inductive relation with the track rails at each bond, signal controlling means, and devices electrically responsive to said coils 55 for governing said signal controlling means.

8. A railway block signaling system having a bond at each end of the block, a bond intermediate the ends of the block, sources 50 of signal controlling current applied to the track rails between said bonds, signal controlling means, a coil in inductive relation with the track rails near each bond and an electro-responsive device connected to each coil and operating independently, for governing the signal controlling means and ar-

ranged and connected to be actuated in one direction or the other according to whether or not the current from the source is diverted from the rails between a source and one of said bonds.

70

9. In a railway block signaling system, a conductively continuous track, bonds of negligible impedance connecting the rails of the track at each end of a block, a bond of negligible impedance connecting the rails intermediate the ends of the block, sources of signal controlling current supplying the track rails at points intermediate said bonds, signal controlling devices, and electro-responsive devices arranged at each bond for 80 governing the action of said signal controlling devices.

75

10. In a railway block signal system, an electro-responsive device at each end of a block, an electro-responsive device intermediate the ends of the block, said devices being in inductive relation to the track rails, and signal controlling means governed by 85 said devices.

85

11. In a railway block signaling system, 90 track rails, means for supplying current thereto, coils in inductive relation with the rails at the ends of the block, a coil in inductive relation with the rails intermediate the ends of the block, a signal and means 95 for actuating the signal responsively to current changes in said coils.

95

12. In a railway block signal system, track rails, coils in inductive relation with the track rails at each end of the block, coils in 100 inductive relation with the rails near the center of the block, means for supplying a signal controlling current to the track rails at points between said coils near the center of the block and the coils at the ends of the 105 block, a signal, means for governing the operation of said signal responsive to the current in said coils.

105

13. In a railway block signaling system, track rails, bonds connecting the track rails 110 at each end of a block, a bond connecting the track rails intermediate the ends of the block, means for supplying a signal controlling current to the rails between the intermediate and end bonds, a coil responsive 115 to current in said rails near one end of the block, a coil responsive to current in said rails near the other end of the block, a coil responsive to current in said rails intermediate the ends of the block, a signal and 120 means for operating said signal responsive to current changes in said coils.

115

14. In a railway block signaling system, track rails, bonds connecting the track rails 125 at each end of a block, a bond connecting the track rails intermediate the ends of the block, means for supplying a signal controlling current to the rails between the bonds, a coil responsive to current in said rails near one end of the block, a coil re- 130

sponsive to current in said rails near the other end of the block, a coil responsive to current in said rails at one side of the intermediate bond, a coil responsive to current in said rails at the other side of said intermediate bond, a signal and means for operating said signal responsive to current changes in said coils.

15. In a railway block signaling system, track rails, bonds connecting the track rails at each end of a block, a bond connecting the track rails intermediate the ends of the block, means for supplying a signal controlling current to the rails between the bonds, a coil responsive to current in said rails near one end of the block, a coil responsive to current in said rails near the other end of the block, coils responsive to current in said rails on both sides of the intermediate bond, a signal, and electro-responsive devices connected to said coils and controlling the operation of said signal.

16. In a railway block signaling system, track rails, bonds connecting the track rails at each end of a block, a bond connecting the track rails intermediate the ends of the blocks, means for supplying a signal controlling current to the rails between the intermediate and end bonds, a coil responsive to current in said rails near one end of the block, a coil responsive to current in said rails near the other end of the block, coils responsive to current in said rails on both sides of the intermediate bond, a signal, a circuit, electro-responsive means in said circuit controlling the operation of said signal and electro-responsive devices so arranged that any one of said coils may control the operation of said electro-responsive means.

40 17. In a railway block signaling system, conductively continuous track rails, means for supplying current to the track rails, coils responsive to current in said rails at the ends of a block, coils responsive to current in the track rails intermediate the ends of the block, a signal controlling circuit and devices responsive to current changes in said coils for controlling said circuit.

50 18. In a railway block signaling system, conductively continuous track rails, bonds at the ends of the blocks, a bond intermediate the ends of the block, means between the intermediate and end bonds for supplying current to the track rails, coils responsive to current in said rails at the ends of a block, coils responsive to current in the track rails intermediate the ends of the block, a signal controlling circuit, and electro-magnetic devices for opening said signal controlling circuit responsive to current changes in said coils.

60 19. In a railway block signaling system, continuously conductive track rails, bonds of negligible impedance connecting the track rails at the ends of a block, a bond of negli-

gible impedance connecting the track rails intermediate the ends of the block, sources of electric current supply intermediate the bonds and at substantial distances therefrom, a signal, signal controlling devices and means for supplying current thereto, responsive to current variations at given points in the rail circuit.

20. In a railway block signaling system, track rails, bonds of negligible impedance at the ends of a block, a signal, signal controlling devices, means for operating part of said devices from either end of a block, and means for operating part of said devices located at a point intermediate the ends of the block.

21. In a railway block signaling system, track rails, a signal, signal controlling devices, means for supplying a signal controlling current to the rails at a plurality of points intermediate the ends of a block, means for operating part of said devices located near the ends of the block and means for operating part of said devices located near the center of the block, said means embracing coils in inductive relation with the track rails.

22. In a railway block signaling system, track rails having blocks, each block having four parts, two sources of signal controlling current supply, each supplying two of said parts, coils each responsive to current in one of said parts and in inductive relation with the track rails, a signal, and devices for operating said signal responsive to current changes in said coils.

23. In a railway block signaling system, track rails having blocks, bonds of negligible impedance at each end of a block, each block having four parts, two sources of signal controlling current supply, each supplying two of said parts, electric devices responsive to current changes in said parts of the block, and a signal controlled by said devices.

110 24. In a railway block signaling system, track rails having blocks, each block having four parts, two sources of signal controlling current supply, each supplying two of said parts, coils, each responsive to current changes in one of said parts, a motor arrangement responsive to each coil in two of said parts, and a signal controlled by each of said arrangements.

120 25. A railway block signaling system having continuously conductive track rails, bonds at each end of a block, a bond intermediate the ends of the block, a source of signal controlling current supply between each pair of said bonds, four coils, each coil being responsive to current changes in the track rails between each source and a bond, a device for each coil and electrically responsive thereto, a signal, a signal controlling circuit and a plurality of switches

arranged to be operated by said devices to open the signal controlling circuit.

26. In a railway block signaling system, a block of track rails having four parts, 5 coils, each responsive to current changes in the rails in one of said parts, a signal, an independent device for controlling the operation of the signal responsive to current changes in one of said coils, an independent 10 device for controlling the operation of the signal responsive to current changes in another of said coils and another device for controlling the operation of the signal responsive to current changes in either of 15 two of said coils.

27. In a railway block signaling system, track rails, means for supplying to the track rails a signal controlling current, coils responsive to currents in portions of said 20 track rails at substantially the ends of a block, coils responsive to currents in portions of said track rails intermediate the ends of the block, said last mentioned coils forming the field and armature coils of a 25 motor arrangement.

28. In a railway block signaling system, track rails, means for supplying to the track rails a signal controlling current, coils responsive to currents in portions of said

track rails at substantially the ends of a 30 block, coils responsive to currents in portions of said track rails intermediate the ends of the block, said last mentioned coils forming the field and armature coils of a 35 motor arrangement, a signal, a circuit, a magnet in said circuit governing said signal, and means on the armature of said arrangement for opening said circuit.

29. In a railway block signaling system, track rails, means for supplying to the track 40 rails a signal controlling current, coils responsive to currents in portions of said track rails which are approximately at the ends of a block, coils responsive to currents 45 in portions of the track rails near the center of the block, a motor arrangement connected to and operated by said last mentioned coils, electro-responsive devices operated by said first mentioned coils and a signal controlled by said motor arrangement 50 and by said electro-responsive devices.

In testimony whereof, I have signed my name to this specification, in the presence of two subscribing witnesses.

CLYDE J. COLEMAN.
